Inventor:

Catherine O'Hara

UNITED STATES PATENT OFFICE.

CATHERINE O'HARA, OF NEW YORK, N. Y., ASSIGNOR TO THE BUTTERICK PUBLISHING CO., (LIMITED,) OF SAME PLACE.

DESIGN FOR A LADY'S COAT.

SPECIFICATION forming part of Design No. 14,430, dated November 20, 1883.
Application filed September 26, 1883. Term of patent 3½ years.

To all whom it may concern:

Be it known that I, CATHERINE O'HARA, of the city, county, and State of New York, have invented and produced a new and original Design for a Pattern of a Lady's Double-Breasted Coat, (numbered 8,871;) and I do hereby declare that the engraved prints accompanying this specification convey to any one accustomed to using paper patterns a clear understanding of how a garment made up by the pattern will appear.

The design combines double-breasted closely-fitted fronts cut away below the closing, and

a closely-fitted back that has laps at the lower parts of its side and side back seams, a roll-¹⁵ing collar and coat-sleeves being added.

What I claim as my invention, and desire to secure by Letters Patent, is—

The design for a lady's double-breasted coat, as shown in the engraved prints accompanying this specification.

CATHERINE O'HARA.
